UNITED STATES PATENT OFFICE.

MELANCTHON T. BURKE, OF LA CROSSE, WISCONSIN.

HAME-FASTENER.

SPECIFICATION forming part of Letters Patent No. 315,714, dated April 14, 1885.

Application filed August 22, 1884. (No model.)

To all whom it may concern:

Be it known that I, MELANCTHON T. BURKE, of La Crosse, in the county of La Crosse and State of Wisconsin, have invented certain new and useful Improvements in Hame-Fasteners; and I do hereby declare the following to be a full, clear, and exact description of the same, reference being had to the accompanying drawings, forming a part of this specification, and to the figures and letters of reference marked thereon.

My present invention relates to that class of harness-fittings adapted for securing together the ends of the hames when placed upon the collar; and it consists, essentially, in combination and arrangements of parts, whereby the said hame-fastener is rendered detachable and adjustable, all as hereinafter more fully described, and pointed out in the claims.

In the accompanying drawings, Figure 1 is a view in perspective of my improved attachment with the fastening-strap partially withdrawn, and Fig. 2 a side view of the same with the strap inserted in place. Fig. 3 is a view in perspective of the locking plate or fitting, showing in outline the manner of securing the straps thereto.

Similar letters of reference in the several figures indicate like parts.

My improved hame-fastener is preferably composed of four parts—*i. e.*, two end clips or hooks, A A', the intermediate locking plate or fitting, B, and the strap C; but, as indicated hereinafter, it may be made in three, five, or more pieces, as desired or deemed most advantageous. The clip A is preferably formed with a perforated cross-bar and an open hook, *a*, though a snap-hook may be used, if desired. The clip A' is also provided with an open hook, *a*', (or a snap-hook may be used,) and a slightly-curved extension or tongue, *a*', perforated, as shown, for the reception of the locking-pin *b*. The locking-plate or fitting B is formed, as shown in Fig. 3, with a perforated web or cross-bar, *b*', having the locking-pin *b* formed upon or secured thereto, the side bars, *b*², and loop *b*³. It is desirable that a slot or opening, *b*⁴, be formed in the forward end of the web *b*' beneath the loop *b*³, to leave room for the passage of the tongue *a*'.

In uniting the several parts together the

strap C, preferably in one piece, is shown, is first passed through the open end of the clip A, then bent down or doubled over the cross-bar and riveted thereto. The shorter end of the strap, perforated for the passage of the pin *b*, is then fitted within the locking-plate B, the extreme end of the strap resting in the slot *b*⁴. In this position a rivet, *b*⁵, is inserted through both thicknesses of the straps and the interposed web or cross-bar *b*'.

As thus constructed and arranged, the fastener is ready for use. The clips A A' are first fastened to the eyes or loops formed upon or attached to the hames by bending down the ends of the hook. The end of the strap is then passed through the opening or loop formed in the hook A', and the two parts are drawn together until the tongue *a*' has been forced the proper distance under the loop *b*³ of the plate B. As soon as the desired adjustment is secured, the tongue *a*' is pressed down over the locking-pin *b*, and the strap is inserted under the loop *b*³, thus securely locking and retaining the parts in their adjusted positions.

To facilitate the passage of the tongue *a*' when drawing or adjusting the two parts together, and also to assist in unhitching, it is found desirable to slightly bevel or round the front edge or corner of the locking-pin and the rear wall of the slots or openings in the tongue *a*'. This arrangement is found especially advantageous in unhitching, as a slight pull on the strap after it is withdrawn from the loop *b*³ will raise the tongue off the locking-pin, thus releasing the clip A'. The clips A A' and fitting B are usually made of malleable cast-iron; but other suitable materials may be employed.

Instead of employing a single strap C and doubling the same on the clip A, I may use two shorter sections and unite them upon the clip A by the rivet in the same way as the doubled strap is there secured, and, if preferred, the clip A and fitting B may be made in one piece; but I prefer to make them separate and unite them by straps, as described, for the reason that I am thus enabled to obtain a strong and more flexible fastener, readily applied to hames as ordinarily constructed, and capable of being quickly and securely adjusted into position and as readily separated for detachment.

Having thus described my invention, what I claim as new is—

1. In a hame-fastener, and in combination with the locking-plate B and clip A, as described, the strap C, doubled upon the cross-bar of the clip A, one end passing over and the other beneath the web of the plate B, said clip and locking-plate being fastened to the strap by rivets, as and for the purpose set forth.
2. In combination with the locking-plate B and clip A, constructed as described, and secured to the strap C, the clip A', provided with a tongue for engagement with the locking-pin and the open hook for the passage of the free end of the strap, whereby the clip A' may be adjusted and secured within the locking-plate by means of the said strap, substantially as described.
3. In a hame-fastener, and in combination with the locking-plate B, provided with the

loop and beveled locking-pin, the clip A', provided with the perforated tongue inserted beneath the loop, and the tightening-strap inserted between the said loop and tongue, said locking-plate B and clip A' being provided with means for attachment to the hames, substantially as described. 25

4. In a hame-fastener, the combination of locking-plate B, provided with the loop and beveled pin, the clip A, strap C, fastened to the locking-plate and clip, and the clip A', provided with an opening for the strap C, and a perforated tongue, said tongue being adapted to engage the pin b, and retained thereon by the strap when drawn under the loop, substantially as described. 30 35
